[57] CLAIM

[21] Appl. No.: 59,440

The ornamental design for a mounting device with suction
cup base for cameras, as shown and described.

[22] Filed: Sep. 11, 1996

DESCRIPTION

[51] LOC (6) Cl. 16-05

FIG. 1 is a front elevational view of a mounting device with
suction cup base for cameras showing my new design;
FIG. 2 is a rear elevational view thereof;
FIG. 3 is a right side elevational view thereof;
FIG. 4 is a left side elevational view thereof;
FIG. 5 is a top plan view thereof; and,
FIG. 6 is a bottom plan view thereof.
